UNITED STATES PATENT OFFICE.

SAMUEL I. DERR, OF EMAUS, PENNSYLVANIA, ASSIGNOR, BY MESNE ASSIGNMENTS, TO UNITED SHOE MACHINERY CORPORATION, OF PATERSON, NEW JERSEY, A CORPORATION OF NEW JERSEY.

EYELETING-MACHINE.

1,281,529.

Specification of Letters Patent. Patented Oct. 15, 1918.

Application filed July 13, 1914. Serial No. 850,644.

To all whom it may concern:

Be it known that I, SAMUEL I. DERR, a citizen of the United States, and residing at Emaus, in the county of Lehigh and State 5 of Pennsylvania, have invented certain Improvements in Eyeletting-Machines, of which the following description, in connection with the accompanying drawings, is a specification, like reference characters on the 10 drawings indicating like parts in the several figures.

This invention relates to improvements in eyeletting machines and contemplates the provision of a machine whereby blind or 15 visible eyelets may be conveniently set in the right and left quarters of a shoe upper after the edges of the latter have been stitched.

Heretofore in this class of work it has 20 been necessary to turn the punched upper nearly inside out in order to locate the setting tools in the desired position. One feature of the invention consists in an upsetting die so mounted that it may be introduced 25 through the lower or unstitched edge of the upper into the required position adjacent to the lacing slit. In the machine herein illustrated the upsetting die is mounted upon the end of a thin bar which is mounted at one 30 side of the setting position and is so arranged that the upsetting die is maintained in alignment with the eyelet carrying set.

Another feature of the invention consists 35 in a movable mounting for the upsetting die so constructed and arranged that it may be moved from one side of the machine to the other, thus facilitating the presentation of a right or left quarter to the machine.

Other features of the invention consist in 40 an adjustable abutment member for supporting the upsetting die during the setting operation and in a stripper for holding the punched part of the upper off the projecting upsetting die and for stripping the clenched 45 eyelet therefrom in order that the feeding of the work from one position to the next may not be hampered.

These and other features of the invention 50 will be best understood and appreciated from the following description of a preferred embodiment thereof selected for purposes of illustration and shown in the accompanying drawings, in which,—

Figure 1 is a view in perspective of por-

tions of an eyeletting machine embodying the 55 present invention;

Fig. 2 is a fragmentary view on an enlarged scale showing the parts of the machine in the position they occupy at the conclusion of the setting operation, and 60

Fig. 3 is a fragmentary view of a shoe upper in which invisible eyelets have been set.

The invention is herein illustrated as embodied in a foot power eyeletting machine of well known construction but it should be 65 understood that the invention is in no sense limited to this type of machine but is of general application.

Referring to the drawings, the machine frame 10 is provided with a bore in which 70 reciprocates a plunger carrying the lower setting die 12. A raceway 34 mounted on one side of the frame 10 is arranged to move forwardly into position to deliver an eyelet to the setting die 12 as the latter is lifted 75 and then to move rearwardly to an inoperative position leaving its endmost eyelet upon the spindle of the die.

In the upper portion 14 of the frame, and in alignment with the path of the lower setting die, there is provided a vertical bore for the spindle 16 upon the upper end of 80 which is journaled a goose neck bracket 20. The spindle 16 is retained in place by a collar 22 secured to its upper end and a collar 85 24 secured to its lower end but is free to turn so that the bracket 20 and the parts carried thereby may be swung from one side of the machine to the other. In Fig. 1 one position of the bracket 20 is shown in full 90 lines and another in dotted lines.

Rigidly secured to the lower end of the bracket 20 is a thin die carrying bar 28 which extends at its outer end into alignment with the lower set 12 and carries on its lower face 95 the upsetting die 32. This, it will be noted, is provided with a downwardly extending centering projection and is disposed in alignment with the lower setting die 12 and maintains its position throughout the range of 100 movement of the bracket 20. By means of this projection the punched work may be located in alignment with the dies. Secured to the bracket below the bar 28 is a spring stripper 30 perforated at its end to permit 105 the passage of the upsetting die 32. The stripper normally stands slightly below the end of the die 32 and thus facilitates the re-

removal of the work from the centering projection and its movement from one setting position to the next.

The lower end of the spindle 16 is threaded 5 for the reception of a cap nut 26 having a rounded end which, pressing upon and acting through the outer part of the upper, reinforces the upsetting die and its carrier against the thrust of the lower setting die 10 12. The nut 26 thus constitutes an abutment the position of which may be adjusted by rotation upon the spindle.

In setting invisible eyelets in the left quarter of an upper the bracket 20 is swung into 15 the position shown in Fig. 1. The quarter, which has previously been punched, is slipped over the bar 28 and the stripper 30 with its lining side down until the holes in the two parts are brought into alinement 20 with the upsetting die 32 with the assistance of the centering projection. In this position the outer or leather portion of the upper 25 lies above the bar 28 while the lining and facing strip 70 lie below the end of the stripper 30. With the work thus positioned the lower setting die 12 is elevated, taking 30 an eyelet from the raceway and inserting its barrel through the hole in the lining and clenching the eyelet against the upsetting die. When the lower die 12 is depressed the stripper immediately removes the clenched eyelet from the centering projection on the upsetting die and the work is free to be fed into position for the next eyelet. In setting 35 eyelets in the right quarter of an upper the bracket 20 is swung substantially into the position indicated in dotted lines in Fig. 1 and the operation is carried out as before, the support for the upsetting die in each case 40 extending outwardly through the unstitched lower margin of the quarter being operated upon.

The machine herein described may be employed with equal facility in the insertion 45 of blind eyelets the only difference being that the work is presented with the lining side uppermost for this class of work.

Having thus described my invention, I claim as new and desire to secure by Letters 50 Patent of the United States:

1. A machine for inserting blind or invisible eyelets having, in combination, a reciprocatory setting die constructed and arranged to carry an eyelet upwardly and insert it in the work from the lower surface 55 thereof, a bracket mounted to swing about an axis disposed substantially at right angles to the plane of the work and in alinement with the path of the reciprocatory setting die, a thin arm extending inwardly from said bracket, a downwardly facing upsetting die mounted in said arm and provided with

a centering projection which extends downwardly below the general level of this arm, and a resilient stripper underlying said arm, 65 and surrounding said die and arranged normally to urge the work out of engagement with the centering projection.

2. A machine for inserting blind or invisible eyelets, having, in combination, a setting die movable to insert an eyelet through the lower of two superposed and punched layers of sheet material, a bracket having an inwardly extending arm and mounted to swing about an axis extending 75 in alinement with the path of the movable die, an upsetting die upon said arm, said arm being arranged to be inserted between said two layers, adjustable means for pressing the material about the hold in 80 the upper layer while the eyelet is being set in the lower layer, and resilient means also supported by said bracket tending to remove the work from the upsetting die.

3. A machine for setting blind or invisible eyelets, having, in combination, a forked frame, a reciprocatory setting die mounted in the lower fork of the frame, a bracket journaled above the upper fork, and an upsetting die carried by said bracket and disposed below said upper fork and in the path 85 of the reciprocatory die.

4. An eyelet setting machine having, in combination, a frame carrying a reciprocatory setting die and a spindle, a bracket 95 mounted on one end of the spindle and an abutment on the other, and an upsetting die carried by the bracket.

5. An eyelet setting machine having, in combination, a co-operating pair of eyelet 100 setting dies, and a stripper pivotally supported upon an axis disposed in alinement with said dies for movement into different positions without disturbing the dies.

6. An eyelet setting machine having, in combination, a movable setting die, a laterally disposed bracket having a thin arm, a co-operating upsetting die mounted upon said arm in alinement with said movable die, a thin resilient stripper arranged substantially 110 around said latter die, attached to said bracket and adapted to lie against said thin arm when an eyelet is being set and to separate the work therefrom when the pressure is relieved, said bracket being mounted for 115 rotation about an axis coincident with the axis of said dies.

In testimony whereof I have signed my name to this specification in the presence of two subscribing witnesses.

SAMUEL I. DERR.
